**RING TYPE POLE PIECES AND METHOD
OF MAKING**

Ray L. Triplett, Bluffton, Ohio, assignor to The Triplett Electrical Instrument Co., Bluffton, Ohio, a corporation of Ohio

Filed Sept. 26, 1958, Ser. No. 763,683

5 Claims. (Cl. 324—151)

This invention relates to electrical instruments and particularly to electrical instruments of the D'Arsonval type and to methods of manufacturing such instruments.

A D'Arsonval type electrical instrument movement comprises a magnetic frame that includes an air gap in which a coil moves against the bias of a spring so that an indication can be had on a dial by a pointer fixed to the coil of the amount of current passing through the coil.

The forming of the magnetic frame is important because the air gap in which the coil moves should be as uniform as possible and the flux distribution along the air gap should be determinable to a high degree, usually being uniformly distributed, and the magnetic frame must have the characteristics of permanence of configuration and be capable of being strongly magnetized.

At the present time a great many such magnetic frames are constructed of sintered steel which is pressed to the desired shape and after assembling a permanent magnet with such pressed steel components, the magnetic frame is finally shaped as to the critical portions thereof including the pole faces that help define the air gap and the portions of the magnetic frame that carry the movement proper which includes the moving coil.

Such sintered steel magnetic frames are expensive in the use of materials and labor and lack the desired permanence of magnetic characteristics.

Having the foregoing in mind, it is a primary object of the present invention to provide an improved magnetic frame structure for an electrical instrument, particularly to the D'Arsonval type.

Another object of this invention is the provision of an improved method of manufacturing a magnetic frame.

A still further object of this invention is to provide a magnetic frame structure for a D'Arsonval type movement in which the various portions of the magnetic frame are rigidly fixed relative to each other at the time of constructing the frame thereby making for an instrument having better characteristics and longer life.

It is also an object of this invention to provide a magnetic frame for an electrical instrument and a method of making the frame which permits the use of cheaper materials without sacrificing any of the desirable qualities of the resulting instrument.

These and other objects and advantages will become more apparent upon reference to the accompanying drawings in which:

Figure 1 is a front elevational view of a typical electrical instrument embodying a magnetic frame according to this invention.

Figure 2 is a sectional view indicated by line 2—2 on Figure 1 showing the mounting of the movement of the instrument in the magnetic frame.

Figure 3 is a sectional view indicated by line 3—3 on Figure 2 showing the portion of the magnetic frame in which the moving coil is mounted.

Figure 4 is a perspective view showing the magnetic frame with the movement portion removed therefrom,

2

Figure 5 is a perspective view showing a single lamination of the magnetic frame in exploded form.

Figure 6 is a plan view showing in detail the arrangement and location of the various parts of the magnetic frame.

Figure 7 is a more or less diagrammatic representation of one manner in which the laminations of the magnetic frame could be formed.

Figure 8 is a sectional view indicated by line 8—8 on Figure 7 showing the punching out of parts of the laminations,

Figure 9 is a sectional view indicated by line 9—9 on Figure 7 showing a step in the manufacture of the laminations wherein brass slugs are struck into the steel laminations,

Figure 10 is a sectional view indicated by line 10—10 on Figure 7 showing a step wherein the brass slugs are expanded into pressure engagement with the surrounding steel,

Figures 11 and 12 are sectional views indicated by lines 11—11 and 12—12 respectively on Figure 7 showing the final steps in the formation of the laminations,

Figure 13 is a view diagrammatically illustrating the riveting together of a stack of the laminations to form the body of the magnetic frame,

Figure 14 illustrates the step of pressure the permanent magnet portion of the frame into position,

Figure 15 diagrammatically illustrates the broaching of the pole faces of the magnetic frame and the notches adjacent the pole faces that receive the sides of the instrument movement, and

Figure 16 illustrates the dipping of the magnetic frame in molten solder.

Referring to the drawings more in detail, the instrument 10 in Figure 1 comprises the usual scale 12 over which a pointer 14 sweeps with the pointer being fastened to a coil that is rotatably mounted in a coil frame so as to make up the instrument movement proper of the instrument and which instrument movement proper is mounted in a permanent magnet frame 16.

In Figures 2 and 3 it will be noted that the bridge frame 18 is preferably a one piece frame, die cast, for example, and that pivot screws 20 and 22 in the ends thereof journal the ends of the pivot shafts that are cemented to opposite ends of coil 24 which consists of a bobbin about which a predetermined number of turns of fine wire are wound.

A biasing spring 26 at one end of the coil may also be utilized for effecting connection of one end of the coil with frame 18 while a spring 28 at the other end of the coil effects connection of the opposite turn of the coil with an arm 30 that is insulated from frame 18. Arm 30 and frame 18 are connected with terminals 32 and 34 and electric current is in this manner supplied to moving coil 24.

Bridge frame 18 has extending between the opposite sides thereof a pair of bridge members 36 and carried by these bridge members is a core 38 of magnetic material.

As will be seen in Figure 3, the coil 24 moves in an air gap defined by core 38, a lower pole face 40 of the magnetic frame and an upper pole face 42.

Pole face 40 is formed on the inside of a ring 44 where as pole face 42 is formed on a relatively small pole member 46. A permanent magnet 48 inside ring 44 engages the said ring and the back of pole member 46 and is effective for magnetizing the magnetic frame.

According to this invention pole member 46 is made rigid with ring 44 by means of brass or other non-magnetic metallic members 50, one at each end of pole member 46. Each member 50 has a tongue 52 extending into a notch in the adjacent end of pole member 46.

and a larger tongue 54, dove-tailed in configuration, extending into the correspondingly shaped notch in the inside of ring 44.

As will be seen in Figures 4 and 5, the magnetic frame 16 is made up of a plurality of individual laminations 56 interconnected by rivets 58. The permanent magnet 48, which is preferably an Alnico such as Alnico VI, is, of course, a single piece of the same front to back dimensions as the assembled laminations.

The inserted non-magnetic members 50 are held tightly in place by being swaged or extruded outwardly after they are in position between ring 44 and pole member 46 as indicated by the depressed portions 60.

According to this invention the laminations are formed in their entirety by punching and pressing operations so that the laminations can be produced rapidly and inexpensively. This also permits the use of rolled steel which is more inexpensive than sintered steel and is more dense, thus providing for more permanence of the magnetic circuit.

It will be seen from Figures 2 through 6 that the pole faces 40 and 42 are separated by notches 62 and which notches receive the sides of the bridge frame 18. The bridge frame is thereby located between the pole faces so that highly accurate assembling of the instrument can be arrived at quite easily. Projections 64 on the sides of frame 18 engage the ends of the magnetic frame and a screw 66 may be employed to clamp the frame in position.

With regard to the manner in which the magnetic frame is manufactured, Figures 7 through 16 reveal diagrammatically the novel method of this invention. In Figure 7 a strip 70 of rolled steel is passed through a series of stations with openings 72 being punched out in one station and which openings are for receiving the brass members 50.

In another station the brass members 50 are forced into the openings 72 and in a following station the members 50 are swaged or extruded into extremely tight relationship with the surrounding steel.

In still another station the strip may have apertures 74, 76 and 78 stamped therein, and in a final station the laminations 56 may be blanked out of the strip. The lamination at this time is completely formed except for the broaching and cleaning up that is to be done thereon after the frame is assembled.

Figure 8 illustrates diagrammatically the step of forming aperture 72 and illustrates punch elements 80 striking out the slugs 82 which are the same shape as the brass members 50.

In Figure 9 a strip 84 of brass is placed on top of the steel strip 70 and using the steel strip as a die, punches 86 strike the brass members 50 from the brass strip and into the apertures 72.

In Figure 10 the brass members 50 are swaged or extruded or smashed out by small punch elements 88 into extremely tight relationship with the surrounding steel and particularly in the region of the key portions formed by the projections 52 and 54 of the brass members.

In Figure 11 punches 90 punch the slugs 92 from the previously mentioned apertures 74, 76 and 78 and in Figure 12 a punch 94 strikes the completed lamination 56 out from strip 70.

Thereafter the proper number of laminations are stacked together, in this case eight, and rivets 96 are placed in aperture 78 and riveted over to fix the laminations together to form the body of the magnetic frame.

At this time the magnet 48 may be pressed in place as indicated in Figure 14 and thereafter a broaching tool 98 may be pressed through the frame to clean up and accurately size the pole faces of the magnetic frame and the notches 62. The entire magnetic frame may then be dipped in molten silver solder, or the like, as indicated in Figure 16, and thereafter a clean up of the pole face areas

will result in a finished magnetic frame. The magnet 48 may be stacked in place as indicated by the stack marks 100, if so desired.

5 The magnetic frame of the present invention exhibits extreme rigidity and excellent magnetic characteristics and is more inexpensive both as to material and labor than previous magnetic frames formed of powdered steel pressed to shape and sintered.

10 The ring formed on the outer portion of the magnetic frame is beneficial because of its shielding effect and also contributes to the rigidity of the magnetic frame. The 15 grooves on opposite sides of the core space that receive the bridge frame 18 provide for extremely accurate alignment of the core and coil in the magnetic frame because the alignment does not depend on the surface flatness of conventional bridge parts fitted to the outside surfaces of the magnetic frame structure as is usually done.

15 It will be understood that this invention is susceptible to modification in order to adapt it to different usages and 20 conditions and, accordingly, it is desired to comprehend such modifications within this invention as may fall within the scope of the appended claims.

I claim:

1. In an electrical instrument; a ring of magnetic material, means defining a first arcuate pole face on the 25 inside of said ring at one side thereof, a generally bar-like member of magnetic material substantially smaller than the space inside the ring located inside the ring and having means defining a second arcuate pole face 30 thereon arranged in opposed relation to the first pole face to define a generally cylindrical region therebetween, non-magnetic metallic elements extending from the ends of said bar-like member to the ring, means rigidly connecting said elements with both the member and the 35 ring, the connection comprising notch means formed in one thereof, and projection means formed on the other thereof extending into said notch means, a non-magnetic frame in the ring between said pole faces, a core in the frame concentric with the pole faces, and a coil rotatable 40 in the frame having side portions in the spaces between said core and pole faces, there being a permanent magnet fitted between the inside of the ring and the side of the bar-like member opposite the side with the pole face thereon.

2. In an electrical instrument; a ring of magnetic material, means defining a first arcuate pole face on 45 the inside of said ring at one side thereof, a generally bar-like member of magnetic material substantially smaller than the space inside the ring located inside the ring and having means defining a second arcuate pole face

50 on one side arranged in opposed relation to the first pole face to define a generally cylindrical region therebetween, non-magnetic metallic elements extending from the ends of said bar-like member to the ring and rigidly connected with both the bar-like member and the ring 55 thereby fixedly and rigidly to support the bar-like member in the ring, the connection between said elements and said bar-like member and ring comprising notches formed in the ends of said bar-like member and on the inside of said ring, and projections on said elements fitted 60 tightly into said notches, a permanent magnet fitted between the inside of the ring and the other side of the bar-like member, a frame fixed in the said cylindrical region, a core in the frame concentric with said pole faces, and a coil rotatably mounted in the frame having side portions in the spaces between the core and the 65 pole faces.

3. In an electrical instrument; a ring of magnetic material, means defining a first arcuate pole face on the 70 inside of said ring at one side thereof, a generally bar-like member of magnetic material substantially smaller than the space inside the ring located inside the ring and having means on one side defining a second arcuate pole face thereon arranged in opposed relation to the first pole face to define a generally cylindrical region

there between, a permanent magnet fitted between the inside of the ring and the other side of the bar-like member, non-magnetic metallic elements extending from the ends of said bar-like member to the ring and rigidly connected with both the bar-like member and the ring thereby fixedly and rigidly to support the bar-like member in the ring, the connection between said elements and said bar-like member and ring comprising notches formed in the ends of said bar-like member and inside of said ring, and projections on said elements fitted into said notches, said projections being expanded into tight gripping relation with the walls of said notches, and at least the notches in the ring and the projections fitted therein being dove-tail in configuration, a frame fixed in said cylindrical region, a core in the frame on the axis of said cylindrical region, and a coil rotatable in the frame having side portions in the spaces between said core and said pole faces.

4. In an electrical instrument; a plurality of annular laminations in stacked relation forming a ring of magnetic material, a bar-like member of magnetic material inside each lamination smaller than the space inside the lamination, non-magnetic, metallic elements extending from the ends of each bar-like member to the inside of the pertaining lamination and rigidly interlockingly connected with the bar-like member and lamination; one side of each said bar-like member and the inside of the pertaining lamination in opposition thereto having arcuate pole faces defining a cylindrical space, the other side of each bar-like member and the inside of the pertaining lamination opposed thereto being parallel whereby the stacked laminations define a first cylindrical space for receiving a core and moving coil and a second space having parallel walls adapted for receiving a block of permanent magnetic material, there being a block of permanent magnetic material in the last mentioned space tightly engaging the lamination and bar-like member, and extending through substantially the complete thickness of the stacked laminations, means fixedly clamping said laminations together whereby the laminations and the block of permanent magnetic material form an integral unit, a frame of non-magnetic material fixed in said cylindrical space, a magnetic core carried by the frame on the axis of said cylindrical space, and a coil rotatably

supported in the frame having side portions in the spaces between said core and pole faces.

5. In an electrical instrument; a plurality of annular laminations in stacked relation forming a ring of magnetic material, a bar-like member of magnetic material inside each ring smaller than the space inside the ring, non-magnetic, metallic elements extending from the ends of each said bar-like member to the inside of the pertaining ring and rigidly connected with the member and ring; one side of said bar-like member and the inside of said ring in opposition thereto having arcuate pole faces defining a cylindrical space, the other side of each member and the inside of the ring opposed thereto being parallel whereby the stacked laminations define a first cylindrical space for receiving a core and moving coil and a second space having parallel walls adapted for receiving a block of permanent magnetic material, there being a block of permanent magnetic material in the last mentioned space tightly engaging the ring and member, and extending through substantially the complete thickness of the stacked laminations, there being means fixedly clamping said laminations together whereby the laminations and the block of permanent magnetic material form an integral unit, there being notches extending outwardly from opposite sides of the said cylindrical space between said member and said ring, a core and coil supporting frame of non-magnetic material having side members positioned in said notches, and a core and coil mounted in said frame.
